CLAIM

The ornamental design for a make up mirror, as shown and described.

DESCRIPTION

FIG. 1 is a front, left and top perspective view of a make up mirror, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of a second embodiment of a make up mirror.

FIG. 10 is a rear, right and bottom perspective view of the second embodiment of the make up mirror of FIG. 9.

FIG. 11 is a front elevation view of the second embodiment of the make up mirror of FIG. 9.

FIG. 12 is a rear elevation view of the second embodiment of the make up mirror of FIG. 9.

FIG. 13 is a left side elevation view of the second embodiment of the make up mirror of FIG. 9.

FIG. 14 is a right side elevation view of the second embodiment of the make up mirror of FIG. 9.

FIG. 15 is a top plan elevation view of the second embodiment of the make up mirror of FIG. 9.

FIG. 16 is a bottom plan elevation view of the second embodiment of the make up mirror of FIG. 9.

FIG. 17 is a front, left and top perspective view of a third embodiment of a make up mirror.

FIG. 18 is a rear, right and bottom perspective view of the third embodiment of the make up mirror of FIG. 17.

FIG. 19 is a front elevation view of the third embodiment of the make up mirror of FIG. 17.

FIG. 20 is a rear elevation view of the third embodiment of the make up mirror of FIG. 17.

FIG. 21 is a left side elevation view of the third embodiment of the make up mirror of FIG. 17.

FIG. 22 is a right side elevation view of the third embodiment of the make up mirror of FIG. 17.

FIG. 23 is a top plan elevation view of the third embodiment of the make up mirror of FIG. 17.

FIG. 24 is a bottom plan elevation view of the third embodiment of the make up mirror of FIG. 17.

FIG. 25 is a front, left and top perspective view of a fourth embodiment of a make up mirror.

FIG. 26 is a rear, right and bottom perspective view of the fourth embodiment of the make up mirror of FIG. 25.

FIG. 27 is a front elevation view of the fourth embodiment of the make up mirror of FIG. 25.

(Continued)

FIG. 28 is a rear elevation view of the fourth embodiment of the make up mirror of FIG. 25.

FIG. 29 is a left side elevation view of the fourth embodiment of the make up mirror of FIG. 25.

FIG. 30 is a right side elevation view of the fourth embodiment of the make up mirror of FIG. 25.

FIG. 31 is a top plan elevation view of the fourth embodiment of the make up mirror of FIG. 25.

FIG. 32 is a bottom plan elevation view of the fourth embodiment of the make up mirror of FIG. 25.

FIG. 33 is a front, left and top perspective view of a fifth embodiment of a make up mirror.

FIG. 34 is a rear, right and bottom perspective view of the fifth embodiment of the make up mirror of FIG. 33.

FIG. 35 is a front elevation view of the fifth embodiment of the make up mirror of FIG. 33.

FIG. 36 is a rear elevation view of the fifth embodiment of the make up mirror of FIG. 33.

FIG. 37 is a left side elevation view of the fifth embodiment of the make up mirror of FIG. 33.

FIG. 38 is a right side elevation view of the fifth embodiment of the make up mirror of FIG. 33.

FIG. 39 is a top plan elevation view of the fifth embodiment of the make up mirror of FIG. 33.

FIG. 40 is a bottom plan elevation view of the fifth embodiment of the make up mirror of FIG. 33.

FIG. 41 is a front, left and top perspective view of a sixth embodiment of a make up mirror.

FIG. 42 is a rear, right and bottom perspective view of the sixth embodiment of the make up mirror of FIG. 41.

FIG. 43 is a front elevation view of the sixth embodiment of the make up mirror of FIG. 41.

FIG. 44 is a rear elevation view of the sixth embodiment of the make up mirror of FIG. 41.

FIG. 45 is a left side elevation view of the sixth embodiment of the make up mirror of FIG. 41.

FIG. 46 is a right side elevation view of the sixth embodiment of the make up mirror of FIG. 41.

FIG. 47 is a top plan elevation view of the sixth embodiment of the make up mirror of FIG. 41; and,

FIG. 48 is a bottom plan elevation view of the sixth embodiment of the make up mirror of FIG. 41.

The broken lines depict portions of the make up mirror that form no part of the claimed design.
